UNITED STATES PATENT OFFICE

2,447,677

HEAVY-DUTY SHIPPING CARTON

Benjamin M. Williams, St. Louis, Mo., assignor
to Gaylord Container Corporation, St. Louis,
Mo., a corporation of Maryland

Application June 16, 1947, Serial No. 754,916

2 Claims. (Cl. 229—14)

1

This invention relates to heavy duty shipping cartons of the kind comprising a tall, tubular open-ended liner and duplicate upper and lower slip covers fitting over the open ends of said liner with their ends in abutting relation. A serious practicable objection to the above type of carton is that the height of the liner prevents the packer from reaching through the opening in the upper end of said liner to the lower portion thereof. The present invention has for its principal object to provide a simple and inexpensive shipping carton of the above type that will permit easy access to be had to the lower portion of the tubular liner to facilitate packing thereof.

The invention consists in providing one side wall of the tubular liner above the lower slip cover therefor with flaps which can be swung outwardly to provide access to the lower portion of said liner and which can be swung back to wall forming position to permit the upper slip cover to be telescoped over the upper end portion of the liner. The invention also consists in the heavy duty shipping carton and in the parts and combinations and arrangements of parts hereinafter described and claimed.

In the accompanying drawing, which forms part of this specification and wherein like symbols refer to like parts wherever they occur.

Fig. 1 is a perspective view of a shipping carton embodying my invention.

Fig. 2 is a perspective view showing the liner mounted in the lower slip cover and the upper slip cover in position to be applied over the upper end of said liner.

Fig. 3 is a perspective view showing the liner mounted in the lower slip cover and the doors of the liner swung open to permit access to be had to the lower portion of the liner; and

Fig. 4 is a fragmentary perspective view of the upper portions of the liner and lower slip cover showing the doors sealed with strips of adhesive tape.

In the accompanying drawing, my invention is shown embodied in a heavy duty shipping carton comprising a relatively tall open-ended tubular liner 1 and duplicate upper and lower slip covers 2 and 3, respectively, all made of corrugated board, fiberboard or other bendable material. The slip covers 2 and 3 are telescoped over the open ends of the liner 1 with their opposing ends in abutting relation. As shown in the drawing, the carton may be bound with crossed metal securing bands or straps 4 that extend around the carton along the top, bottom and sides thereof.

2

and are locked in contracted position by means of suitable coupling members 5.

According to the present invention, one side wall of the liner 1 is slit vertically, as at 6, from the top thereof to a point just above the upper end of the lower slip cover 3 where said wall is also slit horizontally, as at 7. The vertical slit 6 in the side wall of the liner 1 is preferably located midway of the two vertical corners of said liner 10 that are formed in part thereby and the horizontal slit preferably extends from one to the other of said corners, thereby forming in said wall two doors or flaps 9 adapted for horizontal swinging movement into and out of wall forming position about the vertical supporting hinges formed by said corners. By this arrangement, the two doors 9 may be swung outwardly to provide in one side wall of the tall liner 1 above the lower slip cover 3 therefor a side opening 15 through which easy access may be had to the lower portion of said liner for packing. After the liner has been filled through the opening in one side wall thereof, the two hinged flaps or doors 9 are swung back into wall forming position and the upper slip cover is then telescoped 20 over the open end of said liner and serves to hold said doors in such position. As shown in Fig. 4, application of the upper slip cover 2 after packing may be facilitated by sealing the doors 9 shut with strips of adhesive tape 10 applied over the slits 6 and 7.

What I claim is:

1. In a shipping carton comprising a tubular open-ended upright liner of rectangular section and upper and lower slip covers telescoping over the open ends of said liner, the improvement which consists in slitting one side wall of said liner substantially midway of the width of said wall from the top thereof to a point located just above said lower slip cover and slitting said side wall substantially from side to side at said point, thereby forming in said wall two hinged doors adapted, before the application of said upper slip cover to the upper end of said liner, for horizontal swinging movement outwardly out from wall forming position to provide an access opening in said side wall above said lower slip cover.

2. In a shipping carton comprising a relatively tall tubular open-ended upright liner and upper and lower slip covers telescoping over the open ends of said liner, the improvement which consists in slitting one side wall of said liner from the top thereof to a point located above said lower slip cover and slitting said side wall substantially from side to side at said point, thereby forming

in said wall a hinged door adapted, before the application of said upper slip cover to the upper end of said liner, for horizontal swinging movement outwardly from wall forming position to provide an access opening in said side wall above said lower slip cover and adapted in said wall forming position to be covered by said upper slip cover when the latter is applied to said upper end of said liner.

BENJAMIN M. WILLIAMS.
